UNITED STATES PATENT OFFICE.

LEE O. GARRAWAY, OF MEMPHIS, TENNESSEE.

TRIPLE PREHEATER FOR BOILERS.

Application filed October 1, 1924. Serial No. 741,073.

In ordinary preheaters for boiler feed water, the water is heated only once before it enters the boiler. The aim of the present invention is to heat the water in stages so that it will enter the boiler at a considerably higher temperature than ordinarily. In order to accomplish this, exhaust steam is used. This steam is usually wasted and carried from the exhaust passage through the exhaust nozzle directly to the smoke stack.

In the present device the exhaust steam is led from the exhaust nozzle to the feed water supplying device whether an injector or a pump, and on its way to said device the exhaust steam is made to give up heat to the incoming feed water. This feed water is also heated by the shell of the boiler against which the water conduit is laid and lastly before entering the boiler the water is conducted by the conduit through a heating flue within the boiler before finally entering the latter.

In the accompanying drawings, one embodiment of the invention is illustrated, and Figure 1 is a side elevation of a locomotive in partial section;

Fig. 2 is a section on the line 2—2 of Fig. 3 of the heating box or casing through which the feed pipe passes;

Fig. 3 is a section on the line 3—3 of Fig. 1, and

Fig. 4 is a section on the line 4—4 of Fig. 1;

Fig. 5 is a detail section of a double check valve which is employed;

Fig. 6 is a detail section on the line 6—6 of Fig. 5.

In the drawings, the reference numeral 10 represents a locomotive of any modern type. The exhaust steam is led from the exhaust nozzle 11 by a pipe 12 which extends upwardly in the smoke box 30 to the shell of which it is secured in any approved manner. An opening 40 is provided in the smoke box 30 for the exhaust pipe 12 which opens into a casing 13 which extends along the shell 25 of the boiler. This casing is open on its side nearest the shell 25 of the boiler and is attached in any suitable manner, as by bolts 14, to the latter so as to form a steam-tight connection therewith. At the rear end of the casing is formed a pocket 15 from which a pipe 16 is adapted to conduct the steam from the casing to an injector 17. The injector shown conventionally on the drawings is of the lifting type, but it is evident that any other device, such as a pump, may be used

for feeding the water into the boiler. The injector has the usual live steam intake 18, overflow pipe 35 and a cold feed water pipe 19 with the usual valve 20 for admitting the water to the injector, and a valve 21 is disposed in the exhaust steam pipe 16. This valve 21 is open when the injector is in operation in order to admit exhaust steam and condensate from the heater 13 into the injector adjacent the outlet thereof. When the latter is not working, the valve 21 is kept closed to prevent exhaust steam and condensate from entering the injector.

The reference numeral 22 represents a pipe 70 provided with the usual boiler check valve 23. This pipe leads from the outlet of the injector and proceeds, as at 24, through the casing 13. The casing is very shallow, as best seen in Figure 3, so that the portion 24 of the pipe will lie close against the shell 25 of the boiler. The casing is inserted under an asbestos lining 46 and a jacket 47 which usually cover the exterior of the boiler, in this manner preserving the heat as much as possible in the casing. The pipe 24 continues to the forward end of the casing where it makes a short loop and runs out from the casing in a downward direction to a double boiler check valve 26. The pipe continues 75 from said check valve inwardly through the shell of the smoke box, as at 27, to describe a double turn 37 in the longitudinal direction of the boiler within a flue pipe 28 which extends from the fire-box 29 to the smoke box 30 in the usual manner. The pipe then continues in an outward direction through the shell of the smoke box 30, as at 32, and terminates with an intake 31 on the side of the boiler and communicating with the water space of the same. It will now be evident that the feed water after leaving the injector passes through the casing 13, thence proceeding through the pipe 37 in the flue pipe 28 before entering the boiler at 31. While the check valve 26 in itself forms no part of my invention and may be of any known or approved construction, I have shown in Figs. 5 and 6 a valve which I prefer to use. The valve casing 50 is rigidly secured upon the boiler shell and is provided in its upper part with a port 51 alining with a passage through the boiler shell whereby to establish communication with the water space of the boiler. At its outer end, the port 51 opens into a chamber 52 in the valve casing and in the bottom of said chamber is a downwardly flared port

53 forming a seat for the upper end of the double valve body 54 which is of circular cross section and tapered from its middle to both ends, and is freely movable between the ported bottom of the chamber 52 and a web 55 forming a partition between the pipes 24 and 27. An upwardly flared port 56 in the partition in vertical alinement with the port 53 forms a seat for the lower end of the valve.

10 When the injector is working, the water forced through the pipe 24 lifts the valve 54 to the seat 53 and thereby cuts off flow through the port 51 from the boiler, and it will be evident that the feed water is forced 15 through the pipes 27 and 37 into the boiler at the intake 31. When the injector is not working, the valve seats in the port 56 and local water circulation then takes place from the water space of the boiler through the 20 pipes 27 and 37 into the boiler through the intake 31, burning of the pipes being thereby avoided.

The exhaust steam before leaving the casing 13 is made to pass through oil separators 25 34 placed upon ledges 33 in the pocket 15.

The operation of the device is as follows. The exhaust steam is taken through the pipe 12 into the casing 13 and, when the injector is in operation, passes through the oil separating devices in the pocket 15 and continues 30 purified through the pipe 16 into the injector 17 where it condenses when meeting the water passing through the injector, the feed water being thereby heated and the condensate being commingled with the water to again pass through the system. This forms 35 the first heating stage. This partly heated water is then forced through the check valve 23 and the pipe 22. Upon entering the casing 13 through the pipe 24, the preliminarily heated water will be further heated by the exhaust steam freely circulating around the pipe and by the heat rising from the boiler shell. This accordingly forms the second 40 stage of the heater. The thus heated water then passes through the downward continua-

tion of the pipe 24, lifting the valve 26 from its seat, and passes into the bent pipes 27 and 37 where the feed water receives its third and last heating in the flue pipe 28, 50 whence it ultimately enters the boiler through the pipe 32 and the intake 31.

Having thus described the invention, I claim:

1. A feed water heater system for locomotives comprising a continuous water conduit leading from a source of supply near the rear end of the locomotive forwardly upon the shell of the boiler, then into the smoke box of the boiler, then back and forth within a 60 boiler flue and thence into the front end of the boiler, a casing upon the boiler shell housing the portion of the water conduit lying on said shell, a pipe extending from the steam exhaust of the locomotive engines 65 through the smoke box into the front end of said casing, and means for conveying exhaust steam from the rear end of the casing and delivering it into the water conduit at the source of supply in rear of the casing. 70

2. A feed water heater system for locomotives consisting of a continuous water conduit extending longitudinally upon the shell of the locomotive boiler to a point near the front end thereof, then downwardly to a 75 point on the side of the locomotive smoke box and then back and forth within the smoke box and a flue of the boiler, the terminal of said conduit entering the boiler, a heat insulated casing secured upon the shell 80 of the boiler over the longitudinal portion of the water conduit resting thereon, a pipe rising from the exhaust steam outlet of the locomotive engine through the smoke box into the front end of the casing, a pocket at 85 the rear end of the casing, a water-forcing device to the rear of the casing, and a pipe leading exhaust steam from the pocket of the casing into the water-forcing device at the water outlet passage of the same. 90

In testimony whereof I affix my signature.

LEE O. GARRAWAY. [L. s.]
